SORTING DEVICE

Hurley D. Ralston, Oak Park, Ill., assignor to
 Sears, Roebuck and Co., Chicago, Ill., a corpora-
 tion of New York

Application December 5, 1938, Serial No. 243,950

12 Claims. (Cl. 129—15)

This invention relates to improvements in sorting devices of the type having an elongated series of overlapping flaps carried by a movable carriage and adapted for use in sorting and classifying correspondence, bills and the like preparatory to permanent filing.

A principal object of the invention is to provide an improved sorting device of this type which is of strong, simple and light weight construction and large capacity and in which the sorting carriage is guided for reciprocable longitudinal movement to bring the various portions of the series of sorting flaps within convenient arm's reach of the user in a novel manner without the use of a track as has been customary in prior practice.

Another object of the invention is to provide a sorting device of this kind having a carriage controlled for reciprocation in a given path by novel means lying in such path and associated with the under portion of the carriage independently of the sides thereof. In this connection the use of a flexible guiding belt has been found advantageous in practice.

Still another object is to provide a sorting device having a belt-guided movable carriage in which the guiding belt serves not only as the means for controlling the location of the carriage, but also serves as braking means for halting the carriage at the extreme limits of propulsion.

A further object of the invention is to provide a sorting device of the foregoing general character which is equipped for sound deadening to avoid the clatter of moving parts in use.

An additional object is to provide a sorting device in which the movable carriage supports a portable, sectionalized sorting structure providing in the aggregate a relatively long series of sorting flaps and enabling the removal from the carriage of predetermined sections of the series of flaps whereby to facilitate transportation and handling of said sections when loaded.

A still further object of the invention is to provide an improved sorting frame structure for a sorting device of this character in which the sorting flaps are pivotally mounted and supported in a novel manner.

Yet another object of the invention is to provide a sorting device having an improved sorting flap construction.

Other objects and advantages will become apparent in the following description and from the accompanying drawings in which:

Figure 1 is a perspective view of a sorting de-

vice embodying the invention, looking at the device from the front end thereof.

Fig. 2 is a transverse vertical sectional view through the sorting device taken substantially along line 2—2 of Fig. 1.

Fig. 3 is an enlarged fragmental perspective view of a sorting flap used in the device.

Fig. 4 is a fragmental, longitudinal vertical sectional view through the sorting device, with one of the pair of sorting frames omitted.

Fig. 5 is a fragmentary top plan view of the device.

Fig. 6 is a top plan view of a modified form of sorting frame.

Fig. 7 is a rear end elevational view of the modified sorting frame.

Fig. 8 is a vertical sectional detail view taken substantially along line 8—8 of Fig. 7.

Fig. 9 is an elevational view of one face of one of the relatively rigid plates or flaps which are located at the ends of the sorting frames.

Fig. 10 is a fragmentary top plan view of a modified form of the device.

Fig. 11 is a longitudinal vertical sectional view of the last named modification taken substantially along line 11—11 of Fig. 10.

While the invention is susceptible of various modifications and alternative constructions, I have shown in the drawings and will herein describe in detail, the preferred embodiments, but it is to be understood that I do not thereby intend to limit the invention to the specific forms disclosed, but intend to cover all modifications and alternative constructions falling within the spirit and scope of the invention as expressed in the appended claims.

A sorting device of the type with which this invention is concerned is used in sorting and classifying correspondence, bills, orders, and other documentary material preliminary to placing such material in permanent classified files. Where the filing system is of extensive range, the material to be sorted will fall into a large number of subdivisions individually identified by separate sorting flaps disposed close together in a longitudinal series providing pockets therebetween to receive the sorted material. The series of flaps may, however, be of such length that the user will not be able to reach all points of the series within convenient arm's length. Therefore, the series of flaps is mounted upon a carriage adapted to be propelled endwise to bring any selected flaps of the series into convenient position for the operator. For additional convenience in use, the sorting flaps are carried by

supporting structure such as appropriate frames which are removably mounted upon the movable carriage so that after the sorting operation the loaded frames can be carried to the file where the sorted material can be removed from between the flaps and permanently filed away.

As shown by way of example in the drawings, a sorting device embodying the invention may include, generally, an elongated carriage 15 (Fig. 1) supporting a longitudinal series of overlapping, pivoted sorting flaps 16 and mounted upon a base or table 17 for endwise movement in opposite directions to bring any of the flaps into the convenient working range of the user.

In the preferred form, the construction of the carriage 15 (Figs. 1, 2, 4 and 5) is of as light weight as possible commensurate with the necessary strength to adequately withstand normal usage. To this end, the carriage may comprise a pair of elongated side bars 18 and 19 connected together in spaced parallel relation by means of a series of transverse connecting bars 20. The connecting bars are herein shown as of substantially U-shape and four in number secured in parallel relation at predetermined longitudinal points to the opposing faces of the side bars by means such as bolts or screws 21. To facilitate propulsion of the carriage 15, antifriction rollers 22 are provided which are mounted at the respective opposite ends of the side bars 18 and 19.

Herein the side bars 18 and 19 of the carriage are preferably of a light weight, substantially sound deadening construction. Accordingly, these side bars may each be constructed of a pair of flat sheet metal plates 23 connected together in spaced parallel relation on opposite sides of a body 24 formed of a sound-deadening material such as wood. Each bar assembly is connected together in any suitable manner such as by means of the screws 21 and additional bolts or screws 25. The plates 23 extend beyond the opposite ends of the body 24 to receive the rollers 22 which are journaled therebetween on parallel axles 27. Thus, the carriage 15 can be easily propelled over the base 17 with a minimum of effort, and noise possibly arising from movement or clatter of the rollers 22 and other moving parts will be damped by the sound-deadening body 24.

According to the present invention the sorting flaps 16 are mounted in a sectionalized series upon a plurality of similar carrying or sorting trays or frames 28 (Figs. 1, 2 and 4) which are adapted to be removably supported by the carriage 15. These sorting frames 28 may be identically constructed, and a description of one will therefore suffice for the others. Each of the sorting frames 28 preferably includes a pair of elongated side bars 29 and 30 of substantially L-shaped cross section relatively located to provide seats to receive the carriage side bars 18 and 19, respectively. Adjacent to their front and rear extremities, the sorting frame bars 29 and 30 are connected together by means such as respective pairs of spaced parallel rods 31 and 32.

The front connecting rods 31 are so relatively located that one of them will serve as a pivot for the sleeve-like lower end of a relatively rigid metallic end flap or plate 35. The remaining rod 31 is adapted to be engaged by an angular leg 36 at the lower end of the flap plate 35 whereby to limit forward movement of the plate to a predetermined forwardly slanting position. In practice, an angle of about 45° has been found advantageous. Rearward swinging movement of

the flap plate 35 is limited to a substantially vertical position by engagement of the lower end portion of the plate with an additional front connecting bar 37 on the frame.

5 At the rear end of the sorting frame 28, the connecting rods 32 are so relatively located that one of them will serve as the pivot for the lower end of a rear flap plate 38 which is tubularly curled over as at 39 (Fig. 8) to provide a hinge 10 to receive the pivot rod 32. The remaining connecting rod 32 serves as a stop to limit rearward swinging movement of the flap plate 38.

The flap plates 35 and 38 may serve as handles to be conveniently grasped manually for lifting 15 and transporting the sorting frames 28. To aid in gripping the flap plates manually they may be provided with suitable finger grip means such as notches 40 in their opposite longitudinal edges.

20 The sorting flaps 16 are preferably of an improved construction and are removably mounted upon the sorting frame 28 in a novel manner. To this end each of the sorting flaps 16 may comprise a body of suitable flexible material 25 such as pressboard having a visible card holder 41 projecting from the upper end thereof (Figs. 1, 2 and 3). This card holder may comprise a sheet metal plate doubled over to provide spaced parallel legs engaging the opposite sides 30 of the top margin of the sorting flap body and suitably connected thereto permanently as by means of eyelet rivets 42, two such rivets having been found suitable in practice. Alined window openings 43 are provided in both legs of the 35 card holder 41 so that the opposite faces of an index card 44 inserted between the legs may be viewed freely. To facilitate insertion and removal of the index card 44, one of the legs of the holder may be cut away at opposite sides of 40 the holder as at 45 and the opposite leg of the holder may be provided with means for holding the card in place such as a pair of nodes 47 projecting into the cutouts 45. At its lower end, the sorting flap 16 is provided with a hinge 45 formed of a sheet metal plate 48 and secured to the sorting flap body by means of one or 50 more eye rivets 49. A margin of the hinge plate projects beyond the lower edge of the sorting flap body and is curled over to provide a sleeve 50 which is adapted to receive one of a series of spaced parallel pintles 51 (Fig. 2) carried by the sorting frame 28.

The pintles 51 are anchored at one end to 55 one of the sorting frame side bars, herein the bar 30, and project across the intervening space between said bars to lie at their opposite or free end portions upon the upper face of the bar 29. Preferably, the pintles are formed of flexible rod material such as piano wire stock. Therefore, 60 when the hinge sleeve 50 of a sorting flap is to be inserted upon the selected pintle, the free end of the latter will flex upwardly to permit passage of the portion of the wall of the sleeve which is interposed between the pintle and the bar 29. 65 After the sleeve has been fully inserted, the free end portion of the pintle will snap down against the face of the bar 29. Thereafter accidental displacement of the sorting flap by axial movement along the pintle is avoided because the 70 adjacent end of the sleeve 50 will be stopped by engagement with the bar 29. To remove the sorting flap it will only be necessary to flex the pintle so that the hinge sleeve 50 will clear the bar 29 and then slide the sleeve axially off of 75 the pintle.

In order to facilitate guidance of the hinge sleeve 50 onto the selected pintle 51, the upper face of the bar 29 may be provided with suitable guiding means such as a series of spaced studs 52 which, in effect, provide guide grooves therebetween within which the free end portions of the pintles 51 are received. As will be apparent, the sorting flaps 16 may be inserted upon the pintles with either face forward due to the similar size of the sight openings 43 in the card holders whereby either side of the card may be seen with equal facility.

Since the sorting flaps 16 are preferably of a standard length, it will be apparent that they will overlap one another in stepped relation when the series of flaps is swung to rest against the tilted front end flap plate 35, thereby exposing all of the index cards 44 in the holders 41. Items of sorted material are placed in front of or behind selected ones of the sorting flaps 16 by swinging adjacent flaps apart to open the pocket therebetween. Upon releasing the selected flaps after insertion of a sorted item the weight of the superimposed flaps presses them together and clamps the sorted item in place. In this connection it may be noted that the pivoted rear end flap plate 38 lies freely upon the rear sorting flap 16 and by its greater weight aids in the item-clamping action of the flaps. The fixed 45° angle of the front end flap plate 35 of the rear sorting frame 28 will hold the sorting flaps 16 of the rear sorting frame from bearing against the flaps of the foremost sorting frame (Fig. 1). The top surfaces of the sorting frame side bars 29 and 30 serve as rests for the edges of items inserted into the pockets between the flaps, the width of the support thus provided being preferably as narrow as practicable to conserve space and weight, as for example about three and one-half inches.

In order to permit the sorting frames 28 to be removed easily for transportation to the permanent files when loaded, means is employed which will effectively hold the frames in place end to end upon the carriage 15 but will quickly release either frame when the latter is lifted away. For this purpose each of the side bars 18 and 19 of the carriage 15 has secured at the center of its inner face an upwardly projecting frame-engaging member 53, of T-shape in the part thereof which extends above the upper face of the associated side bar. These T-members 53 are adapted to engage over the adjacent ends of the side bars 29 and 30 of the sorting frames when the latter are moved into place by a longitudinal sliding motion. When fully in position relative to the T-members 53, the adjacent ends of the sorting frames 28 are held against upward displacement from the carriage 15. As a result, the length of the carriage 15 may be substantially less than the aggregate length of the two sorting frames 28 which can project cantilever fashion beyond the respective opposite ends of the carriage. The weight of each supporting frame assembly also assists in holding it in place.

Longitudinal movement of the sorting frames upon the carriage 15 is avoided in a suitable manner as by engaging within notches 53^a in one of the sorting frame side bars, herein the bar 29, appropriately located pins 53^b projecting rigidly inwardly from the carriage side bar 18. By having the notches 53^a and the pins 53^b on but one side of the sorting frames 28, they will serve to assure proper placement of the sorting

frames because if the notches do not register with the pins, the latter will hold the sorting frame against properly seating upon the carriage 15. Thus, the two sorting frames will be held against relative longitudinal displacement when pressure is applied thereagainst as in propelling the carriage forwardly or rearwardly or in manipulating the sorting flaps. However, either sorting frame can be easily and quickly lifted from the carriage.

As shown, the base or table 17 may be constructed as a portable, elongated platform which may be carried from place to place. Wood or other suitable materials may be used to construct the body of the base 17 and if desired a sound-deadening topping 54 of linoleum or the like may be placed upon the base to assist in dampening noise. Suitable legs 55 may be provided for the base 17 to support the same at spaced points in raised relation to a supporting surface. These legs may be rubber tipped for gripping the under-surface frictionally to avoid undesirable shifting of the device.

Herein the carriage 15 is guided in a novel manner for movement longitudinally of the base 17 by means which lies under the carriage and is associated therewith independently of the side bars 18 and 19 and the rollers 22. An endless guiding belt 56 may be provided for this purpose, running over a pair of spaced pulleys 57 respectively located adjacent to the opposite ends of the base 17, within suitable apertures 58 in the base and passing both above and below the base. This belt may be made of any suitable material but is preferably formed of steel being highly flexible for movement perpendicular to its major plane but substantially non-yielding, though possibly slightly resilient, in such plane. Desirably, spaced hangers 59 depending from the lower face of the base 17 support the lower span of the belt 56 from engaging the surface upon which the device is standing.

The span of the guiding belt 56 is substantially greater than the length of the carriage 15 and means is provided for connecting the ends of the belt to the carriage below the sorting frames 28. Accordingly, the ends of the belt are provided with fixed attachment means such as clamps 60 which are detachably connected together by means such as a lockable turnbuckle connector 61. By means of the turnbuckle 61 the belt 56 can be adjustably tensioned for optimum efficiency. In order to hold the belt to run with the carriage, the clamps 60 are provided with stops 62 projecting endwise therefrom and adapted to engage with the screws 25 on the side bars 18 and 19 of the carriage, such screws being spaced apart sufficiently to permit some longitudinal play between the carriage and the belt and thus relieve possible operating strains that may arise in use.

Strain upon the carriage 15 and the guiding belt 56 is further relieved by the novel manner of threading the belt into engagement with the carriage. Accordingly, the U-shaped connecting bars 20 of the carriage 15 are utilized to engage the guiding belt 56 in such a manner that the belt will guide the carriage 28 for rectilinear movement but will permit slight lateral yielding of the carriage from said path due to the flexibility and slight twisting or buckling play of the belt when sufficient lateral pressure is applied. However, the resiliency of the tensioned belt which tends at all times to resist twisting and to return the belt to its normal plane will draw the car-

riage back into its rectilinear path. As may be seen in Figs. 4 and 5, the guiding belt 56 is threaded under the endmost connecting bars 20 and over the innermost connecting bars. Moreover, the outer connecting bars are located with their webs downwardly to hold the belt adjacent to the top of the base 17 while the inner connecting bars 20 are located with their webs upwardly to hold the portion of the belt threaded thereover sufficiently above the top of the base 17 to clear the connecting clamps 60 and turnbuckle 61. Upwardly projecting bosses 63 on the inner connecting bars 20 serve to define ways for receiving the guiding belt 56 and prevent undesirable side play of the carriage relative to the belt. As a result of this arrangement, the carriage is guided for easy rectilinear longitudinal movement over the flat base 17 practically noiselessly and with substantially less liability to frictional restraint than where, as in prior devices, the carriage runs on a track, the relatively non-yieldability of the guide belt 56 transversely in its plane assuring that the carriage will be held to its rectilinear course.

An advantage of the threaded arrangement of the guiding belt 56 resides in the braking effect of the belt acting through the innermost connecting bars 20 over which it passes. When the carriage has been moved to its forwardmost position as seen in Fig. 4, the belt, acting between the forward pulley 57 and the adjacent inner connecting bar 20, will create a retarding pressure which will stop forward propulsion of the carriage without jarring or undesirable backlash. The same action takes place between the guiding belt and the rearward one of the inner connecting bars 20 and the rear pulley 57 when the carriage is propelled rearwardly. In practice it has been found that this retarding or braking effect operates effectively even though the carriage may be propelled with unnecessary vigor.

For sorting many types of papers, the narrow width of sorting frames 28 is ample, the aggregate weight of the flaps lying upon one another being generally sufficient to hold the sorted papers in place in spite of the narrow base, provided by the sorting frame side bars 29 and 30. In some instances it may be desirable, however, to have a wider base for the sorted papers, and for this purpose means such as detachable horizontal plates or wings 65 (Figs. 6 and 7) may be provided for extending the sides of the frames. These wings 65 may be constructed as flat sheet metal plates adapted to be secured interchangeably at either side of the sorting frame by means of screws 67. These screws pass through tongues 68 extending laterally from the attaching edges of the extension wings to straddle the series of upwardly projecting guide bosses 52 when the respective extension wing 65 is secured to the frame side bar 29.

On occasion it may be desired to use one of the sorting frames 28 independently. In such event, because of the short length of the sorting frame it will not be necessary to shift it for ready access to any of the sorting flaps 16 thereof. For such use, however, it will be desirable to hold the frame fixedly in place; and means may be provided for this purpose such as suction cups 69 (Figs. 7 and 8) which may be threadedly attached to the front end connecting bar 37 and to a supplemental rear end connecting bar 37a on the sorting frame.

In the modified form of the invention shown in Figs. 10 and 11, the carriage 15 is guided by a fixedly attached flexible belt 70 along which

the carriage is slibably shiftable. The guiding belt has the opposite ends thereof anchored to a suitable base or table 71 over which the carriage is movable. One end of the guiding belt 70 is engaged by fixed securing means such as a clamp device 72 and the other end is engaged by securing and tension-adjusting means 73. The latter may comprise an anchor plate 74 rigidly secured to the table 71 and a movable plate 75 permanently secured to the end of the guiding belt 70. Holding the plate 75 down upon the table 71 are screws 77 passing through slots 78 in the belt-engaging plate 75 and permitting a limited range of movement of this plate longitudinally of the guiding belt 70. Connecting the two plates 74 and 75 is an adjusting member such as a turnbuckle screw 79 threaded into flanges 80 on the plates and adapted to be locked in adjusted position by means such as nuts 81. Preferably, the fixed securing means 72 and the adjustable securing means 73 are suitably recessed into the table 71 so as to clear the carriage 15 which will run substantially therebeyond similarly as is the case with the pulleys for the endless belt 56.

25 The guiding belt 70 is threaded through the transverse connecting bars 20 of the carriage 15 similarly as the belt 56 but will slide through these bars as the carriage is propelled in either direction along the belt. The braking effect of 30 the belt 70 will be the same. Preferably, the surfaces of the bars 20 which are engaged by the guiding belt 70 will be rounded off to reduce friction. If desired, of course, the bars 20 can be equipped with antifriction rollers, or specially 35 supported rollers for engaging the belt can be provided.

From the foregoing it will be apparent that the present invention provides an efficient sorting device of large capacity and simple, strong 40 and light weight construction. An important factor in maintaining the weight at a minimum resides in the use of the thin flexible steel belt for guiding the sorter carriage instead of the heavier track structures as heretofore employed. 45 Moreover, the sectionalized sorting flap structure affords a substantial advantage in handling the flaps when loaded and also permits the flaps to be used as smaller units. In other respects also, the present invention improves upon sorting devices of this character.

I claim as my invention:

1. A sorting device of the character described comprising, in combination, a base structure, an elongated carriage movably carried by said base structure and having a longitudinal series of overlapping sorting flaps swingable about parallel axes transverse to the longitudinal axis of said carriage, rollers at the sides of said carriage for anti-friction engagement of said base, said series of sorting flaps being of a length greater than normal arm's reach, and means cooperating with said carriage inwardly spaced from and independently of said rollers below said flaps for guiding movement of said carriage longitudinally when said carriage is propelled over said base to bring any selected sorting flaps of the series within convenient arm's reach of the user.

2. Sorting apparatus of the character described comprising, in combination, a base structure, a carriage movable over said base structure, a fixedly anchored guiding belt for said carriage, and means on said carriage for slidably engaging said guiding belt to enable guided movement of the carriage therealong.

3. A sorting device of the character described

comprising, in combination, a movable carriage, a pair of elongated trays each having a series of sorting elements cooperating to provide pockets therebetween for receiving sorted material, said trays being adapted to be supported by said carriage in end-to-end relation to combine the individual series of sorting elements thereof into a continuous series, and means on said carriage for removably engaging said trays to hold the latter at least in part against upward displacement.

4. A sorting device of the character described comprising, in combination, a supporting structure, a pair of elongated sorting frames each having a series of sorting elements thereon, said frames being adapted to be mounted upon said supporting structure in end-to-end relation, means on said supporting structure for holding the adjacent ends of said frames against upward displacement, and interengaging means on said frames and on said supporting structure for holding said frames against endwise movement relative to said supporting structure.

5. A sorting device of the character described comprising, in combination, a carriage including a frame having a pair of spaced parallel side bars, and means for connecting said bars rigidly together, said bars each comprising spaced metallic face plates and sound deadening means between said face plates.

6. A sorting device of the character described comprising, in combination, a sorting frame having a pair of spaced parallel side members, mechanism on said frame providing sorting pockets and having means on the upper face of one of said members spaced inwardly from each end of the latter and maintaining a predetermined spaced relationship of the sorting pockets, and an extension wing plate having attachment ears straddling said means and secured to said one member.

7. A sorting device of the character described comprising, in combination, a sorting tray including an aligned series of pintles anchored at one end and extending in spaced parallel relation toward one side of the tray, a series of sorting flaps including hinges removably engageable with said pintles, said flaps providing a plurality of sorting pockets therebetween, means for removably supporting said tray generally horizontally above a base, and means on said supporting means partially overlying said tray for holding said tray and said supporting means together in a predetermined assembled relationship.

8. A device of the character described comprising, in combination, a base structure including a substantially plane supporting surface, a carriage movably supported upon said surface, means for holding said carriage to a rectilinear path of movement over said surface including as the sole guiding element a belt held to a given longitudinal span relative to said base and with its major transverse plane disposed across the top of said surface, and means providing an operative connection between said belt and said carriage enabling the carriage to be moved freely in said path while maintaining constant guiding

association with said belt, said belt being freely flexible perpendicular to its major plane but substantially resistant to flexure within such plane so that it may move in a direction toward or away from said supporting surface in the rectilinear travel of said carriage but will substantially prevent lateral displacement of said carriage from said path.

9. In combination with a movable carriage and a plane base supporting said carriage for travel in a rectilinear path thereover, a guiding belt under said carriage held to a fixed span in face up relation longitudinally in said path and being flexibly movable toward or from said base at intermediate points in said span but substantially immovable laterally, and means on said carriage engaging said belt both facewise and loosely edgewise for continuous guiding association therewith, the facewise engagement being such as to hold the carriage against separation from said base and the edgewise engagement being such as to retain the carriage substantially in predetermined longitudinal alignment with the belt.

10. A sorting device of the character described comprising, in combination, a carriage for supporting a removable sorting tray, a plane base, a belt for guiding said carriage in a rectilinear path over said base, said belt lying flatwise between said carriage and said base and being flexible facewise but relatively non-yielding edgewise, means on said base connecting said belt to said base and confining said belt to a predetermined longitudinal span permitting facewise flexure relative to said base within said span but holding the belt substantially against lateral movement relative to said base, means operatively connecting said carriage to said belt, and means for adjusting the tension of said belt to limit flexure thereof and thereby the possible range of separating movement between said carriage and said base.

11. A sorting device of the character described comprising, in combination, a low carriage constructed to be readily movable over a flat base, a sorting tray removably supported in a horizontal plane by said carriage and having means projecting upwardly therefrom defining a series of sorting pockets, and means located under said sorting tray for guiding said carriage in a predetermined path when the latter is moved over the base and having engagement with said carriage for holding the latter against removal from the base.

12. A device of the character described comprising, in combination, a carriage including spaced parallel side members, a base over which said carriage is adapted to be moved, a guide belt confined to a predetermined span upon said base, and a plurality of spaced parallel transverse bars extending between said side members, said guide belt being threaded through said transverse bars whereby to connect said carriage to said base and guide its movements in a predetermined path over the base.

HURLEY D. RALSTON.
